[57]

ABSTRACT

A timer having switch means responsive to a cam programming means, the cam programming means being driven through a timer motor through a clutch operated drive means. The cam programming means and the switch means are disposed within a housing. Electrical terminals are mounted in the housing and extend through the housing and are unitarily constructed with the switch means. The motor electrical leads are connected to the switch means and the terminal means inside the housing through a quick disconnect means. The clutch drive means comprises a gear means having ratchet means adapted to engage corresponding ratchet means on the cam programming means.

**CAM OPERATED PROGRAM TIMER ASSEMBLY
WITH REPLACEABLE LEAF SPRING CONTACT
STRUCTURE**

This application is a continuation of application Ser. No. 731,228, filed May 22, 1968, now abandoned.

Defrost timers have long been used in appliances such as refrigerators. The timing mechanisms of such timers are generally used to defrost refrigerators in accordance with a predetermined program cycle. The timers are usually motor driven through their own separate motor means, the motor means deriving its power from the power source of the refrigerator or components thereof.

In the manufacture of these timers, industry is constantly striving to make the timers as small and compact as possible with a minimum number of parts. Also, the industry is highly competitive and therefore the most economical fabrication methods are constantly being sought. Therefore, not only must the timer be as small and as compact as possible, but it must be of such a construction which is economical to produce.

The present invention is concerned with the provision of a defrost timer and has as one of its objects the provision of such a timer which is compact, with a minimum number of parts.

Another object of the invention is to provide a defrost timer having such an arrangement of parts that it is economical to produce.

Another object of the invention is to provide a defrost timer having motor-driven cam programming means and switch means responsive to the cam programming means.

Still another object of the invention is to provide a defrost timer wherein the cam programming means and the switch means are enclosed in a housing.

Another object of the invention is to provide a defrost timer where its electrical terminals are unitarily constructed with the switch means.

Another object of the invention is to provide a defrost timer wherein the electrical terminals are crimped along their edges so as to stiffen the terminals without using relatively thick material for the terminals.

Yet another object of the invention is to provide a defrost timer wherein the electrical terminals are lanced for mating with notches formed in the timer housing carrying such terminals.

Still another object of the invention is to provide a defrost timer wherein the electrical leads for the timer motor are connected to the electrical terminals and the switch means inside the timer housing through a quick disconnect means.

A further object of the invention is to provide a defrost timer wherein the quick disconnect means comprises jacks having oppositely formed legs lanced from the terminals and the switch means.

Another object of the invention is to provide a defrost timer having clutch means to alternately engage and disengage the cam programming means from the timer motor.

Yet still another object of the invention is to provide a defrost timer wherein the clutch means includes spring-biased gear means having ratchet teeth adapted to engage corresponding ratchet teeth of the cam programming means.

Another object of the invention is to provide a defrost timer wherein manual operating means are provided to rotate the cam programming means independent of the gear means such that the timing sequence of the cam means can be manually set.

Other objects of the invention and the nature thereof will become apparent from the following description considered in conjunction with the accompanying drawings and wherein like reference numbers describe elements of a similar function.

For illustrative purposes the invention will be described in conjunction with the accompanying drawings in which:

FIG. 1 is a front view of the defrost timer with portions thereof being removed to show the various elements of the timer.

FIG. 2 is a section taken along line 2-2 of FIG. 1;

FIG. 3 is a side view showing the relationship of the timer motor to the timer housing with a portion being removed to show the electrical terminals; and

FIG. 4 is an enlarged isometric view of an electrical terminal block with the terminals.

Generally speaking, the objects of the invention are accomplished by providing a defrost timer which in general comprises a housing, a motor for the timer mounted on the housing, cam programming means and switch means responsive to the programming means, both of which are disposed within the housing, drive

means connecting the motor to the cam programming means, a plurality of electrical terminals extending into the housing, at least one of which is electrically connected to the switch means, and electrical leads electrically connecting the motor to two of the terminals through quick disconnect means disposed within the housing. The drive means includes clutch means; the clutch means includes a spring-biased gear means having ratchet teeth adapted to engage corresponding ratchet teeth of the cam programming means.

Referring now to the drawings, the various elements of a defrost timer 10 are enclosed in a housing 12, the housing being formed from a cut-shaped member 17 which is closed by a cover plate 14. A constant speed motor 16 is connected to cover plate 14, the motor being used to drive a cam programming means 18. Cam programming means includes oppositely opposed hub portions 20 and 66, the programming means being unitarily constructed with the hub portions. Hub portions 20 and 66 are journaled in cover plate 14 and cup-shaped member 17 respectively. The motor drives cam programming means 18 through a drive means 22. Drive means 22 includes a pinion 24 and a gear 26. Gear 26 "floats" on hub portion 20. Pinion 24 is connected to a shaft 28 of the motor. Spring 30 biases the gear 26 between the cam programming means 18 and the cover plate 14. Gear 26 has ratchet teeth 32 adapted to mate and engage corresponding ratchet teeth 34 formed on the cam programming means 18.

Switch means 36 consisting of a plurality of switch blades 38 is responsive to cam programming means 18 through an arcuate step 40 formed on the cam programming means. The arcuate step consists of a constantly rising lobe ending in a sudden drop 40'. Cover plate 14 has a projecting portion 15 adapted to mate a corresponding cut-away portion 11 formed in cup-shaped member 17. Cut-away portion 11 has notches

11' and 11" adapted to receive corresponding tongues 15' and 15" of projection 15. Terminals 44 are carried in slots 13 formed in cup-shaped member 17, the slots being closed by projection 15. Terminals 44 are used to complete the electrical circuit to the elements to be controlled in a manner hereinafter described. The terminals may be, as is more clearly shown in FIG. 4, unitarily constructed as an integral molded structure with a terminal block 42. Terminal block 42 would then be inserted in an aperture formed in cup-shaped member 17, the aperture being formed to receive the block. Also as is shown in FIG. 4, tongue 43 is slightly larger than tongue 43', such that the terminals will be properly aligned with respect to the cam programming means 18 when the block is inserted in a housing constructed similar to housing 12.

Switch blades 38 are, as shown, preferably formed as a single unitary unit with terminals 44. With such a construction, the terminals with the blades become easier, and consequently more economical to form. And, in addition, they are more easily fabricated with the unit as a whole. As is more clearly shown in FIGS. 3 and 4, the terminals 44 have crimped edges 46. The use of the crimped edges effectively stiffens the terminals such that they more readily mate the female portions of leads connected to the terminals in that the tendency for the terminals to bend has been substantially eliminated. This construction is especially effective where the terminals and the switch blades are unitarily constructed. That is, the stiffness of the terminals can be effectively increased without increasing the thickness of the blade such that the blade's bending characteristics will not be impaired. In order to prevent any slippage of the terminals, the terminals are lanced to form small, curved-out projections 48 which are received by notches 50 formed in the cup-shaped member 17 and having restraining walls transverse to the lengthwise direction of the blades and terminals. The terminals are additionally lanced to form curved projections 49 which when mated with corresponding mating notches in the female plug provide a positive electrical connection between the two.

Motor leads 52 and 54 are connected to the terminals and the switch means 36 through quick disconnect means 56. As shown, the leads are connected within the housing 12, thus eliminating the need for a shroud over the terminals 44 which is necessary when the terminals would be connected outside the housing. This again reduces the cost of fabricating the timer and, in addition, renders the timer more compact. Quick disconnect means 56 comprises a jack having oppositely formed legs 58 and 60 lanced from the terminals and the switch means. The quick disconnect means eliminates the need of soldered joints which are commonly found in timers such as these, thus again reducing the cost of fabricating the timer, and in addition makes it easier to change the leads when occasion demands it.

Switch blades 38 each carry electrical contacts 62, 62' and 62" such that when the contacts are brought together in a predetermined sequence, an electrical circuit can be completed through the blades and the electrical terminals. The blades are separated by a slidable separating means 64 which is mounted in suitable apertures 67 formed in the blades. Rotation of cam pro-

gramming means 18 causes the contacts 62, 62' and 62" to be engaged in a predetermined programmed sequence in a manner hereinafter to be described.

Having described the various elements of the present defrost timer, its operation can now be discussed. As shown, leads 52 and 54 are electrically connected to terminals 44' and 44", the terminals being electrically connected to a power source. Such power source is within the refrigerator, for example, the refrigerator motor. Thus the motor for the timer is constantly running so long as the refrigerator is operating. For safety purposes there is also a ground wire connection 70 attached to the housing 12. The present timer is so constructed so as to alternatively operate, in a predetermined cycle, a cooling means such as a compressor for the refrigerator and a defrost means such as a suitable heating means. Motor 16 drives gear means 26 through pinion 24, the gear means in turn driving cam programming means 18 through ratchet teeth 32 and 34. Ratchet teeth 32 and 34 are continually engaged so long as the timer is operating. As shown in FIG. 1, contacts 62' and 62" are engaged to complete an electrical circuit through terminal 44". Terminal 44'" would complete the electrical circuit to the refrigerator compressor, for example, such that when contacts 62' and 62" are engaged, the refrigerator will be in the cooling cycle. Contacts 62' and 62" will be engaged when the contacts are riding on the rise portion of the lobe of cam means 18. Contact 62 will remain separated from contact 62' due to separator means 64. When contact 62' drops off the rise lobe of cam means 18, contacts 62 and 62' will become engaged by virtue of separating means 64 sliding a sufficient amount to allow the contacts to become so engaged. With contacts 62 and 62' engaged, an electrical circuit is completed through terminal 44, terminal 44 being connected to a defrost means such as a suitable heating means.

The timing cycle of the timer can be manually adjusted through slot 68 formed in hub 66. Inserting a screwdriver into slot 68 enables cam programming means 18 to be independently rotated from gear means 26 by virtue of ratchet teeth 34 riding over ratchet teeth 32, there being sufficient axial "play" between the gear means and the cam programming means through spring 30, and by virtue of the fact that gear 26 floats on cam hub 20.

Thus there is described a defrost timer which is compact with a minimum number of parts which is therefore more economical to produce both in terms of the number of parts and in the fabrication techniques necessary to manufacture the timer. The motor means 25 are connected to the terminals within the motor housing thus eliminating the need for a shroud over the electrical terminals. The terminals are unitarily constructed with the switch means, which contributes to the timer's economical construction. Further, the leads are connected to the terminals and the switch means through quick disconnect means such that expensive soldered or welded joints need not be used. The terminals have crimped edges such that female leads can be easily connected to the terminals through the effective increasing of the stiffness of the terminals without increasing its overall thickness. The clutch means consisting of the spring biased gear having ratchet teeth to engage cor-

responding ratchet teeth of the cam programming means is simple with a minimum number of parts making it easily manually adjustable for changing the timing of the cam programming means.

We claim:

1. In a timer having motor driven cam programming means:

- a. a cup shaped housing and a cover closing same, said cam programming means carried within said cup-shaped housing,
- b. slots provided across a cut-away portion of a wall of said cup-shaped housing, said cover including a projection adapted to mate said cut-away portion and close said slots,
- c. at least two one-piece combination plug-in electrical terminals and movable switch blades carried in said slots, the plug-in electrical terminal portion of said one-piece combination extending through at least a substantial portion of said wall in said slots,
- d. projections lanced from said one-piece combination adapted to be received in notches provided in said wall and opening to said slots, said notches having restraining walls transverse to the lengthwise direction of said one-piece combination preventing any substantial lengthwise slippage of said one-piece combination,
- e. said movable switch blades extending substantially linearly beyond the ends of said plug-in electrical terminal portions so as to be cantilevered through the cooperation of said plug-in electrical terminal portion and said wall, said movable switch blades responsive to said cam programming means, and

f. cooperating electrical contacts carried at the free ends of said movable blades.

2. In a timer according to claim 1, wherein said electrical terminals and said switch means are unitarily constructed.

3. In a timer according to claim 2, wherein said terminals are crimped along their edges.

4. In a timer according to claim 1, wherein said plug-in electrical terminal portion extends through said 10 housing wall and terminates about at the inner face of said housing wall.

5. In a timer according to claim 1, wherein said plug-in electrical terminals are crimped along their edges.

6. In a timer according to claim 1 further including 15 electrical leads connecting said motor to two of said electrical terminals.

7. In a timer according to claim 6 wherein said electrical leads are electrically connected to said motor through quick disconnect means disposed within said 20 housing.

8. In a timer according to claim 1 further including clutch means to alternately engage and disengage said cam programming means from said motor.

9. In a timer according to claim 8 wherein said clutch 25 means includes spring biased gear means coupled to said motor and having ratchet teeth adapted to engage corresponding teeth carried by said cam programming means.

10. In a timer according to claim 1 further including 30 manual operating means coupled to said cam programming means.

ABSTRACT

A timer having switch means responsive to a cam programming means, the cam programming means being driven through a timer motor through a clutch operated drive means. The cam programming means and the switch means are disposed within a housing. Electrical terminals are mounted in the housing and extend through the housing and are unitarily constructed with the switch means. The motor electrical leads are connected to the switch means and the terminal means inside the housing through a quick disconnect means. The clutch drive means comprises a gear means having ratchet means adapted to engage corresponding ratchet means on the cam programming means.
